poration, Tulsa, Okla., a corporation of Okla-
homa

Original application April 15, 1942, Serial No.
439,056. Divided and this application August
14, 1944, Serial No. 549,414.

4 Claims. (Cl. 304—14)

This is a division of application Serial Number 439,056, filed April 15, 1942, now Patent No. 2,358,755 granted Sept. 19, 1944.

This invention relates to improvements in derrick structures of the conventional portable type having a working or pipe racking platform of the foldable type normally employed therewith, and particularly to an improved hinge structure for connecting such platforms with such derrick structures.

In the construction, operation and use of portable type derrick masts, now in wide use in oil fields, it is especially desirable that all the elements of the mast and the various appurtenant appliances be so arranged and connected as to be quickly and easily set up and taken down, to form a compact structure, which may be transported from place to place on trucks operating over standard highways.

To meet this requirement, it is now the practice 20 to hingedly connect platforms, such as the conventional pipe racking platforms, to the mast structure so that such platforms may be compactly folded against the mast when not in use. By using a hinged connection, it is not necessary to dis-assemble the platform from the rest of the mast structure, when it is out of use or when the mast is to be lowered for transporting to another location. This arrangement has the important disadvantage, among others, that the elevational position of the platform on the mast is necessarily fixed, and in order to change the relative elevation of the platform it must be removed from the mast and moved to the desired elevation. In ordinary well drilling operations, it is frequently desirable to change the elevation of the pipe racking platform for the purposes of safety and convenience of workmen standing on the platform. The elevation of the platform is generally determined by the length of the pipe sections being run in and out of the well, it being desirable that the upper end of each pipe section extend above the platform to a height which is particularly adapted for the convenience of and safe handling by the workmen. Commercial standards for the lengths of drill pipe and tubing sections permit substantial variations of from four to eight feet in the length of each section, depending upon the particular classification of the pipe. Thus, a string of pipe employed in one case may be made up of sections of substantially greater or lesser length than those employed in another operation with the same mast structure. With the working platform fixed at an elevation suitable for the proper handling of

the pipe in one case, the elevation will be inconvenient and unsafe for the handling of the pipe in the other case and it becomes necessary to change the elevation of the working platform accordingly.

5 A principal object, in accordance with this invention, is to provide an improved form of hinge structure whereby the elevation of a working platform on a mast may be varied while retaining the hinged connection of the platform to the mast at any elevation, and without bodily disconnecting the platform from the mast.

Other objects and advantages of this invention will become apparent from the following detailed description when read in conjunction with the accompanying drawings which illustrate useful embodiments in accordance with this invention.

In the drawings:

Fig. 1 is a side elevation of a mast and platform assembly employing a hinge structure in accordance with one embodiment of this invention;

Fig. 2 is a perspective view of the platform and mast assembly of Fig. 1, showing an enlarged view of the details of the hinge structure more generally illustrated in Fig. 1;

Fig. 3 is a side elevation in enlarged detail of the embodiment of Fig. 1;

Fig. 4 is a plan view of the structure of Fig. 3;

Fig. 5 is a rear elevational view of one side of the structure of Fig. 3 along line 5—5 and looking toward the front of the structure;

Fig. 6 is a view similar to Fig. 5 but having a section cut therethrough along line 6—6 of Fig. 3;

Fig. 7 is a perspective view, partly in section, showing the details of the hinge structure of Figs. 1 to 6;

Fig. 8 is a side elevation in enlarged detail of another embodiment of a hinge structure in accordance with this invention;

Fig. 9 is a plan view of the structure of Fig. 8;

Fig. 10 is a rear elevational view of one side of the structure of Fig. 8 taken generally along line 10—10 thereof;

Fig. 11 is a sectional elevation taken along line 11—11 of Fig. 8; and

Fig. 12 is a perspective view, partly in section, showing the details of the hinge structure of Figs. 8 to 11.

Referring to the drawings and to Fig. 1 in particular, the upper portion of derrick mast, indicated generally by the numeral 1, has mounted thereon, a platform, indicated generally by the numeral 2, which may be a working platform or

a pipe racking platform of any suitable or conventional type. Platform 2 is hingedly connected to the front of the mast by means of a hinge structure indicated generally by the numeral 3, which is adapted to be movable with the platform vertically along the mast while maintaining the hinged connection of the platform with the mast. A cable 4 leads from the usual drilling rig hoisting mechanism (not shown) over a pulley 5, mounted on the crown of the mast, and is connected by means of a suitably formed bridle 6 to platform 2 and hinge structure 3, for the purpose of changing the elevation of the platform on the mast or of folding the platform against the mast.

Derrick mast 1 is of the conventional "open-front" type having a pair of front corner posts 7-7 and a pair of rear corner posts 8-8 arranged to form the corners of a structure which is generally rectangular in cross-section. Rear corner posts 8-8 are connected to each other and to front corner posts 7-7 by means of suitable girts 9 and braces 10.

Platform 2 consists of a conventional U-shaped frame formed of spaced parallel side members 11-11 connected together at the forward ends by an end member 12. The frame encloses a platform area, including the usual floored sections 13-13 and open working section 14 to permit free movement therethrough of the usual hoisting mechanism and pipe (not shown) and pipe racking area 15-15 for the reception of the pipe being handled. The usual guard rails 16-16 are mounted on the frame and enclose the platform area in the usual manner for the protection of men working on the platform.

Hinge structure 3, in accordance with the embodiment illustrated in Figs. 1 to 7, inclusive, comprises a pair of hinge arms, designated generally by the numeral 17, each constructed of a pair of hinge plates 18, spaced apart and set on edge, which are rigidly attached along their lower edges to the free ends of side members 11 of the platform frame. A pair of laterally spaced parallel rails, designated generally by the numerals 19-19, are positioned between corner posts 7-7 and are vertically supported from the mast 1 in general alignment with the inner edges of hinge arms 17. The supports for rails 19-19 consist of a pair of upright members 20-20 spaced rearwardly from rails 19-19 and aligned therewith and supported between upper and lower cross-members 21 and 22, respectively, which extend horizontally across the mast between suitably positioned side girts 9. Each of rails 19 is rigidly connected to a corresponding upright member 20 by means of a plurality of vertically spaced tie plates 23 which extend from the rear faces of the rail to the upright members 20. Each of the rails 19 is formed from a pair of channel iron members 24, the channels of which face toward each other, the edge flanges extending at right angles to the planes of hinge arms 17. The inner edges of the hinge arms extend into the channels of members 24 between the flanges thereof. The upper portion of the inner edge of each hinge arm carries a sleeve 25 extending transversely thereof and provided with an axial bore 26 adapted to register with a registering pair of journal openings 27-27 provided in the webs of channel members 24. A plurality of such pairs of journal openings 27 are provided at vertically spaced points along each of the channel members, a removable pivot pin 28 extends through the bore 26 and a pair of the journal openings 27

to complete the pivoted connection of each hinge arm to the corresponding rail 19. Sleeve 25 has end portions of reduced diameter adjacent the contiguous channel member 24 to form axles 29-29 for a pair of rollers 30-30 which are freely revolvable thereon and are held in place by the webs of the channel members. Rollers 30 are adapted to bear on the inner faces of the flanges of channel members 24. A pair of idler rollers 31-31, carried on a shaft 32 which extends through the pair of plates 18-18 forming each hinge arm, are positioned on opposite sides of the hinge arm and are arranged to bear on the outer faces of the front edge flanges of channel members 24. A pin 33 extends transversely through each pair of plates 18-18 and provides a means for connecting a strand of bridle 6 thereto.

In operation, when it is desired merely to fold the platform inwardly against the mast, the forward strands of bridle 6 are connected to loops 34 positioned at intermediate points along side members 11 of the platform and a pulling force is applied to cable 4. The platform will swing upwardly and inwardly toward the mast about pivot pin 28 as an axis. When it is desired to change the elevation of the platform, the bridle strands are connected to pins 33 and loops 34. Pivot pins 28 are withdrawn from rails 19 and sleeves 25. A pulling force applied to cable 4 will now lift the platform bodily, hinge arms 17 moving upwardly between channel members 24. Since rollers 30 are confined within the channels, the platform is not detached from the mast, and rollers 30, together with idler rollers 31, which bear on opposite sides of the edge flanges, will render the upward movement of the platform relatively frictionless. When sleeve 25 has attained a position registering with the pair of journal openings 27-27 at the elevation desired, pivot pin 28 is reinserted, the bridle released, and the platform is ready for service in the new elevation.

Figs. 8 to 12, inclusive, illustrate another embodiment in accordance with this invention. In this embodiment, the channel iron members 24 of rails 19 are placed back-to-back with the channels thereof facing in opposite directions. In other respects these rails are similar to those of the previous embodiments, having vertically spaced journal openings 27, and being supported from the mast in the same manner as previously described.

Each hinge arm 17 is formed by a pair of spaced parallel generally triangularly shaped plates 35-35, the inner edges of which extend over the outer sides of members 24, enclosing the channels therein. The upper ends of plates 35-35 carry a pair of rollers 36-36 which are mounted to roll in the channels of members 24. These rollers are mounted on hollow trunnions 37-37 which extend inwardly from the exterior of plates 35-35 into the channels. A locking pin 38 is removably inserted through the bore of trunnions 37-37 and registering journal openings 27 in members 24 to lock the hinge arms to the rail. Since rollers 36-36 are mounted on the trunnions, which are fixed in place in the hinge plates, they retain their position when locking pin 38 is withdrawn. A second pair of rollers 39-39 are mounted on a second pair of trunnions 40-40, carried by the lower ends of plates 35-35 and are also arranged to roll in the channels and to lock the lower ends of plates 35-35 to the channel members. The forward portions of plates 35-35 are pivotally connected to the ends of side members 11 of platform 2 by means of pivot pins 41-41 which ex-

tend transversely through the plates 35-35 and the ends of side members 11. Plates 35-35 are provided with the pin 33 for attachment of bridle 6.

In the operation of this embodiment, when it is desired to change the elevation of platform 2, bridle 6 is attached to loops 34 and pins 33. Locking pins 38 are withdrawn, and the platform moves along rails 19 on rollers 36 and 39 under the control of cable 6. When rollers 36 reach a position opposite the journal openings 27 at the desired elevation, locking pins 38 are re-inserted through trunnions 37, rollers 36 and these openings 27 and the platform is locked in its new position. The hinged connection of platform 2 to hinge plates 35 by means of pivot pins 41 permits the platform to be folded toward the mast by pull applied to loops 34 through bridle 6 and cable 4. With this embodiment also, it will be seen that the elevation of platform 2 may be varied without disconnecting the platform from the mast, and without affecting the ability to fold the platform toward the mast at any elevation.

It will be understood that various changes and modifications may be made in the details of this invention within the scope of the appended claims without departing from the spirit of this invention.

What we claim and desire to secure by Letters Patent is:

1. In a derrick structure having a platform mounted thereon to swing generally between horizontal and vertical positions, an improved hinge structure for connecting said platform to said derrick structure comprising, a pair of laterally spaced rails vertically supported from said derrick structure, said rails having spaced edge flanges extending longitudinally thereof forming guide channels in said rails, a plurality of longitudinally spaced journals positioned along said channels, hinge arms extending from the sides of said platform toward said channels, pairs of vertically spaced rollers carried by said hinge arms and rollably disposed in said channels, a pivoted connection between said hinge arms and the sides of said platform, and removable locking members

extending through one of the rollers of each pair and a selected one of said journals along each of said channels.

2. In a derrick structure having a platform mounted thereon to swing between generally horizontal and vertical positions, an improved hinge structure for connecting said platform to said derrick structure comprising, a pair of laterally spaced rails vertically supported from said derrick structure, hinge arms carrying roller members rollably connecting said hinge arms to said rails, a pivoted connection between said platform and said hinge arms, and removable locking members adapted to extend through said rollers and said rails to lock said hinge arms to longitudinally spaced points along said rails.

3. In a derrick structure having a platform mounted thereon to swing between generally horizontal and vertical positions, an improved hinge structure for connecting said platform to said derrick structure comprising, a pair of laterally spaced rails vertically supported from said derrick structure, triangular-shaped hinge arms carrying vertically spaced pairs of rollers adapted to provide a maintained longitudinally movable connection with said rails, a pivoted connection between said platform and the hinge arms, and removable locking members extending through said rollers and said rails for locking said hinge arms to longitudinally spaced points along said rails.

4. In a derrick structure having a platform mounted thereon to swing between generally horizontal and vertical positions, an improved hinge structure for connecting said platform to said derrick structure comprising, a pair of laterally spaced rails vertically supported from said derrick structure, hinge arms having a pivoted connection to said platform and carrying roller members providing a rollable connection to said rails, and removable locking members extending through said roller members and said rails for locking said platform at vertically spaced positions along said rails.
